FURNACE

Warren Dean Burton, Goshen, Ind., assignor, by
mesne assignments, to The Steel Products En-
gineering Company, Springfield, Ohio, a corpo-
ration of Ohio

Application December 13, 1930, Serial No. 502,041

10 Claims. (Cl. 126—182)

This invention relates to furnaces for burning solid fuel and more particularly to those of the so-called overfeed type.

One object is to provide a new and improved grate construction which is universally adaptable to furnaces of different sizes, which facilitates ash elimination and which improves combustion efficiency by effecting proper agitation of the fuel bed.

Another object is to provide a novel means for actuating the grate above referred to.

A further object is to combine a power-actuated overfeed stoker with a movable grate construction and an ash removing mechanism so that the stoker motor may be utilized to actuate said grate and said mechanism.

The invention also resides in the novel character of the driving connection between the stoker and the ash conveyor.

Further objects and advantages of the invention will become apparent from the following detailed description taken in connection with the accompanying drawings, in which

Figure 1 is a fragmentary sectional view of a furnace embodying the novel features of the present invention and equipped with a stoker which is shown substantially in elevation.

Fig. 2 is a front elevational view looking from the left in Fig. 1.

Fig. 3 is a fragmentary plan view of the grate construction and the supporting means therefor.

Fig. 4 is a sectional view taken along the line 4—4 of Fig. 3.

Fig. 5 is a sectional view of the grate support and ash conveyor as viewed along the line 5—5 of Fig. 1.

Figs. 6 and 7 are fragmentary views of the grate illustrating modifications of the means for effecting vertical agitation of the fuel bed.

Fig. 8 is an elevational view partially in section showing a modified form of the ash remover drive mechanism.

Fig. 9 is a sectional view of the driving connection between the stoker and ash conveyor.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The furnace shown in the drawings has the usual fire-box defined by a circular downwardly converging wall 10 and adapted to be supplied with solid fuel such as coal by a power driven automatic stoker 11 of well-known construction supported in front of the furnace upon a movable truck or tripod 12. The stoker includes a hopper 13 arranged to discharge coal into a trough 14 along which the coal is fed through the fire-door of the furnace by a conveyor such as a screw 15 and finally discharged onto a grate later to be described and generally designated by the numeral 16.

The coal conveyor is driven through speed reduction gearing (not shown) by an electric motor 17 which, according to common practice, may also drive a blower 18 for forcing air for combustion through conduits 19 extending through the fire-door and also the draft door 20. Manual operation of the coal conveyor may be effected by turning a crank 21 on a shaft 22 included in the driving connection between the motor 17 and the screw 15.

Means arranged to be actuated automatically as an incident to the operation of the stoker is provided for removing ashes from the furnace. In the present instance, this means comprises a screw 23 (Figs. 1 and 5) disposed in a horizontal trough 24 which extends substantially the entire length of the furnace ash-pit and projects outwardly through the draft door 20. The inner end portion of the trough 24, which is supported by legs 25, has upwardly flaring side walls 26 which define an ash receptacle which receives the ashes falling through the grate 16 and deflects the same onto the screw 23.

The screw 23 is on a shaft 27 which is journaled in a bearing provided by the inner end wall of the trough 24. Outside of the furnace the trough 24 is closed and communicates with the casing 28 of a conveyor 29 preferably of the bucket type for receiving the ashes withdrawn from the furnace by the screw 23 and moving them laterally to the desired point of disposal. The outer end of the shaft 27 is journaled in the casing 28 and carries a gear 29 for driving the bucket conveyor.

The conveyor for removing ashes is intended to be driven by power derived from the stoker motor 17. To this end, the shaft 27 is extended forwardly from the furnace through the medium of a rugged universal coupling 30 (Figs. 1 and 9), a squared shaft 31 telescoping with a squared tubular sleeve 32 which in turn is joined by a coupling 33 to a shaft 34 journaled in a bearing 35 and thereby supported by the front leg of the

tripod 12. By providing this telescoping connection, the stoker unit may be removed conveniently and wheeled away from the furnace without withdrawing or otherwise disturbing the ash conveying mechanism.

In order that the ash remover and stoker may be operated by hand independently of each other under certain conditions, a one-way connection is preferably employed between the stoker motor 10 and the shaft 34. This connection, in the preferred form shown in Figs. 1 and 2, comprises a link 36 pivotally connected at one end to the free end of the crank 21. The other end projects loosely through the free end of a bifurcated 15 crank 37 loose on the shaft 34 and carrying a weighted pivotal pawl 38 normally engaging the teeth of a ratchet wheel 39 fast on the shaft 34. The free end of the crank 37 is disposed between two adjustable stops 40 on the link 36 so as to 20 form a lost motion connection the slack in which may be adjusted as desired to vary the extent of rotary motion which will be imparted to the conveyor screw 23 in each revolution of the crank 21. Thus during operation of the stoker motor, 25 reciprocation of the link 36 will advance the screw 23 intermittently in a direction to carry ashes out of the furnace.

The one-way drive formed by the pawl 38 and ratchet 39 permits the ash conveyor screw 30 to be turned independently of the stoker operation as by means of a hand crank (not shown) applied to the outer end of shaft 34, the pawl riding over the ratchet teeth. When the coal conveyor becomes obstructed, it is necessary to 35 rotate the same reversely by turning the crank 21 by hand. This will not, however, effect reverse rotation of the ash conveyor in view of the pawl and ratchet connection.

Instead of driving the ash conveyor screw 40 intermittently, it may be turned continuously during operation of the stoker by means of the one-way connection shown in Fig. 8. In this modification, a sprocket wheel 41 fast on the shaft 22 drives an endless chain 42 to rotate a sprocket 45 loose on the shaft 34 and having teeth 44 rigid therewith which are adapted to engage lugs 45 on the shaft 34 and rotate the latter in a direction to convey ashes out of the furnaces when the stoker is operating to feed coal into the furnace. 50 A compression spring 46 urges the sprocket 43 into engaging relation with respect to the lugs 45 but permits retraction of the sprocket when the inclined surfaces 47 of the teeth are engaged by the lugs 45 as will be the case when the shaft 55 34 or the sprocket 41 is turned in a direction reverse to its normal direction of rotation. The one-way connection thus provided permits operation of the stoker independently of the ash remover when it is desired to remove an obstruction and also independent operation of the ash 60 remover. If desired, the driving connection may be enclosed by a plate 48 through which the squared ends of the shafts 22 and 44 extend for application of cranks for hand operation.

65 Now referring more particularly to Figs. 1, 3, 4, and 5, the grate 16 upon which the bed of fuel is supported during combustion comprises generally a perforated circular plate or disk 50 forming a shallow or flattened cone which is mounted for continuous rotation relative to the fuel bed and about an upright axis. The grate perforations are in the form of elongated radially extending slots 51 which, in the rotation of the disk, move around the under surface of the fuel bed 70 and allow the finer ash particles to fall through

the plate into the upwardly opening ash receptacle.

Owing to the sloping character of the upper grate surface, the clinkers or larger ash particles work out toward the peripheral edge of the grate 5 which is formed with closely spaced squared projections 52 which are adapted to cooperate with a fire-box wall of predetermined size to define openings through which the lumps of ash partially fall. In the rotation of the grate, the projections 52 apply sudden impacts to the lumps of ashes wedging the lumps against the furnace wall and effectively breaking them into smaller pieces which eventually fall through the peripheral grate openings.

In order to render the grate adaptable universally to fire-boxes of different sizes and therefore applicable to existing furnaces, the disk 50 is made to fit a small size furnace. For a larger fire-box, it is preferred to employ a substantially 20 flat adapter ring 53 of the proper radial width to fill the annular space between the fire-box wall and the notched periphery of the disk 50. The ring has its outer peripheral edge notched for the purpose above described and may be supported 25 by the disk 50 through the medium of annularly spaced lugs 54 formed integral with the ring and overlying the edge of the disk so as to rest upon the upper surface thereof. The ring 53, being only slightly larger than the plate 50, is 30 properly held concentric with the plate.

The grate is rotatably mounted upon a rugged frame structure disposed within the ash receptacle and in the present instance including a ring 55 having a diameter slightly less than that 35 of the disk 50 and constituting a substantially circular horizontal track upon which rest a plurality of spaced lugs 56 depending from the under side of the disk. One side of the ring is flattened as indicated at 57 (Fig. 3) and has radially projecting arms 58 which rest in notches formed in the curved end wall 59 of the ash receptacle. The diametrically opposite side of the ring is formed with two integral legs 60 (Fig. 5) which rest upon ledges formed by the sides of the trough 24. 40 Radial spokes 61 terminate at the center of the ring in an upstanding stud 62 over which fits a hub flange 63 depending from the under side of the disk 50 at the center thereof. The stud 62 thus defines an upright axis about which the 45 grate is adapted to turn while the major portion of the weight of the fuel bed is sustained by the track 55 around which the lugs 56 slide during rotation of the grate.

The rotary motion of the screw shaft 21 of the 55 ash conveyor is utilized in the present instance to impart relatively slower unidirectional movement to the grate for the purpose of shaking down the ashes as above described. To this end, a pinion 64 fast on the inner end of the shaft 21 60 meshes with a gear 65 which rotates on a horizontal stud 56 projecting into the ash receptacle from the flattened portion of the end wall 59. The upper portion of the gear 65 is thus disposed opposite the flat portion 57 of the ring 65 and above the level of the lugs 56 which constitute gear teeth. Integral with and projecting laterally from the gear 65 is a lug 67 which, in each revolution of the gear, enters the space between two of the lugs 56, engages one of them, 70 and advances the grate through a small angle. Thus in the operation of the conveyor screw 23 an intermittent and unidirectional movement is imparted to the grate at a substantially reduced speed.

It has been found that in a furnace construction of the above character, a considerable improvement in combustion efficiency is obtained by agitating the fuel bed preferably in a vertical direction. While this action may be obtained in numerous ways, it is preferred to cast the disk 50 so that the axis 68 of its upper conical surface will be inclined slightly relative to the truly vertical rotational axis 69 of the disk which is defined by the stud 62. To compensate for this inclination of the two axes, the lugs 56 are formed of different lengths as will be apparent from Fig. 4 so that in all angular positions of the disk, their lower ends will rest upon the track 55. It will be seen, therefore, that as the plate rotates through each complete revolution relative to the fuel bed, each portion of the fuel bed supported on the grate will be raised and lowered once through a distance corresponding to the angular relation of the axes 68 and 69. A slow and progressive agitation of the fuel is thereby effected with this arrangement without bodily vertical movement of the grate relative to its support.

Inasmuch as the grate is actuated by means deriving power from the stoker motor, it will be apparent that the fuel bed will be agitated and the fire thereby enlivened only when the demands on the furnace as determined by the usual controlling thermostat warrant such an increase in the rate of combustion. Thus, after the thermostat has ceased to call for heat and a slow rate of combustion is desirable for the sake of fuel economy, the fuel bed remains undisturbed.

In the modified form shown in Figs. 6 and 7, vertical agitation of the fuel bed is effected by the cam action of the lug 67 on one side of the grate disk 50. For this purpose the gear 65 is mounted so that the lug 67 not only engages and advances a depending lug 56 of the disk but also strikes the under side of the disk and momentarily raises the latter. In the same rotary motion of the disk, a lug 56 on the opposite side of the disk will ride over a stationary cam lobe 70 formed on the track 55. The result of this arrangement is to raise and lower the grate bodily each time it is advanced by rotation of the gear 65.

I claim as my invention:

1. A grate for supporting a bed of fuel in a furnace fire-box comprising a circular perforated plate adapted to be mounted in said fire-box for rotation about a vertical axis to present the grate openings to successive sections of the fuel bed, the upper surface of said plate being shaped to form a cone the axis of which is inclined relative to the rotational axis of the grate and the peripheral edge of which is located in a plane inclined to the horizontal.

2. In a furnace having a circular combustion chamber, in combination, an annular horizontal track having a flattened portion at one side, a stationary bracket adjacent said portion, outwardly extending arms on said track resting on said bracket, depending supporting legs on said track opposite said arms, a plurality of radially converging spokes rigid with said track, a vertical bearing stud supported by said spokes axially of said track, a conical circular grate disk bearing centrally on said stud and having an axis inclined to said stud, an annular series of depending projections uniformly spaced about said stud and formed on the under side of said disk for engagement with said track, said projections varying in length to compensate for the inclination of said disk, a rotary gear member pivotally mounted on said bracket and having means adapted for

engagement with said projections outside of said flattened portion of said track to rotate said grate disk, and means for rotating said gear member.

3. In a furnace, in combination, an annular horizontal track having a flattened portion at one side, a stationary bracket adjacent said portion, a plurality of converging spokes rigid with said track, a vertical bearing supported by said spokes axially of said track, a conical circular grate disk mounted centrally on said bearing and having an axis inclined to said bearing, an annular series of depending projections uniformly spaced about said bearing and formed on the under side of said disk for sliding engagement with said track, said projections varying in length to compensate for the inclination of said disk, and drive means mounted on said bracket for engaging said projections outside of said flattened portion to rotate said disk.

4. In a furnace, in combination, an annular horizontal track, a vertical coaxial bearing supported by said track, a circular grate disk mounted centrally on said bearing, said disk being inclined to its axis of rotation, an annular series of depending projections uniformly spaced about said bearing and formed on the under side of said disk for sliding engagement with said track, said projections varying in length to compensate for the inclination of said disk, and means for engaging said projections to rotate said disk.

5. In a furnace, in combination, means defining a horizontal annular track, a vertical bearing supported in coaxial relation to said track, an inclined grate member mounted centrally on said bearing for rotation in a horizontal plane, annularly arranged depending means rigid with the under side of said member and concentrically about said bearing for engagement with said track, said depending means varying in height to compensate for the inclination of said member, and means for turning said member on said bearing.

6. In a furnace, in combination, means defining a horizontal annular track, a vertical bearing supported in coaxial relation to said track, an overfeed grate member resting centrally on said bearing for rotation in a horizontal plane upon said track, annularly arranged depending lugs rigid with the under side of said member and concentrically about said bearing for engagement with said track, a gear rotatable on a horizontal axis, and a lug carried by said gear and revoluble thereby periodically into engagement selectively with said lugs to impart a unidirectional step-by-step rotation to said member.

7. An overfeed grate member adaptable to furnace fire-boxes of different diameters comprising a perforated substantially circular plate arranged for rotation on a substantially vertical axis, the peripheral edge of said plate being formed with a series of closely spaced outward projections substantially throughout its circumference, an adapter ring having an internal diameter slightly greater than the diameter of said plate and removably secured concentrically to said plate, said ring having a plurality of spaced inwardly extending lugs adapted to overlie and engage said plate and having means coacting with said projections to prevent rotation relative to said plate, the outer peripheral edge of said ring being formed with a series of closely spaced outwardly extending projections.

8. In a furnace, in combination, means defining a horizontal annular track, a vertical bearing stud supported in coaxial relation to said track,

- a grate member mounted for free vertical movement centrally on said stud and for rotation in a horizontal plane, annularly arranged spaced depending means on the underside of said member and concentrically about said stud for engagement with said track, vertical lift cam means on said track, and drive means coacting with said depending means to rotate said member and in the course of such rotation to move said depending means periodically over said cam means so as to elevate and lower said member.
9. In a furnace, in combination, means defining a horizontal annular track, a vertical bearing stud supported in coaxial relation to said track, a grate member mounted for free vertical movement centrally on said stud and for rotation in a horizontal plane upon said track, annularly arranged spaced depending means on the underside of said member and concentrically about said
- 10 stud for engagement with said track, and drive means comprising a lug carried by a rotating member periodically coacting with said depending means and the underside of said grate mem-

ber to simultaneously impart vertical and rotary movement to the grate member.

10. In a furnace, in combination, means defining a horizontal annular track having a flattened portion on one side, a vertical bearing stud supported in coaxial relation to said track, a grate member mounted for free vertical movement on said stud and for rotation in a horizontal plane on said track, annularly arranged spaced depending means on the underside of said member 10 and concentrically about said stud for engagement with said track, vertical lift cam means on said track opposite the flattened portion thereof, and drive means adjacent the flattened portion of said track comprising a lug carried by a rotat- 15 ing member and periodically coacting with said depending means and the underside of said grate member to elevate one side of the grate member and to rotate the same over said cam means and simultaneously elevate the other side of the grate 20 member.

WARREN DEAN BURTON.
